UNITED STATES PATENT OFFICE

MILTON A. RUSH, OF SAN FRANCISCO, CALIFORNIA

DESIGN FOR A RADIO LEG REST

Application filed June 7, 1930. Serial No. 35,970. Term of patent 7 years.

To all whom it may concern:

Be it known that I, MILTON A. RUSH, a citizen of the United States, residing at 378 Golden Gate Avenue, San Francisco, in the county of San Francisco and State of California, have invented a new, original, and ornamental Design for Radio Leg Rests, of which the following is a specification, reference being had to the accompanying drawing, forming part thereof.

Fig. 1 is a top plan view of a radio leg rest showing my new design.

Fig. 2 is a side view of the illustration in Fig. 1.

I claim:

The ornamental design for a radio leg rest, as shown.

MILTON A. RUSH.
